[57] **CLAIM**

The ornamental design for a motorcycle belly pan, as shown and described.

DESCRIPTION

FIG. 1 is a perspective view of my motorcycle belly pan showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front view thereof; and,

FIG. 7 is a rear view thereof.

The broken lines depicting the extended portion of the motorcycle belly pan forms no part of my invention.
